CLAIM

The ornamental design for a lid of a charger box as shown
and described.

DESCRIPTION

FIG. 1 is a bottom/left perspective view of a lid of a charger
box;

FIG. 2 is a bottom/right perspective view thereof;

FIG. 3 is a bottom view thereof;

FIG. 4 is a top view thereof;

FIG. 5 is a left side view thereof;

FIG. 6 is a right side view thereof;

FIG. 7 is a front view thereof;

FIG. 8 is a rear view thereof; and,

FIG. 9 is a rear view with environmental lines removed.

The broken lines illustrate the environment of the lid of a
charger box and form no part of the claimed design.

1 Claim, 9 Drawing Sheets
